DESIGN FOR A MEDALLION CHARM

Marjorie G. Josselyn, Woodside, Calif.

Application June 30, 1937, Serial No. 70,186

Term of patent 14 years

To all whom it may concern:

Be it known that I, Marjorie G. Josselyn, a citizen of the United States, residing at Woodside, county of San Mateo, State of California, have invented a new, original, and ornamental Design for a Medallion Charm, of which the following is a specification, reference being had to the accompanying drawing, forming a part thereof.

Fig. 1 is a front view of the medallion charm with the design thereon in relief, the rear side being plain.

Fig. 2 is a vertical sectional view of the medallion charm taken along line 2—2 of Fig. 1.

I claim:

The ornamental design for a medallion charm, substantially as shown and described.

MARJORIE G. JOSSELYN.
